UNITED STATES PATENT OFFICE.

HUBERT LONGAUER, OF MILWAUKEE, WISCONSIN.

EXTERMINATOR.

1,264,194.

Specification of Letters Patent. Patented Apr. 30, 1918.

Application filed March 1, 1918. Serial No. 219,802.

To all whom it may concern:

Be it known that I, HUBERT LONGAUER, a citizen of the United States, residing at Milwaukee, in the county of Milwaukee and State of Wisconsin, have invented certain new and useful Improvements in Exterminators, of which the following is a specification, reference being had to the accompanying drawing, forming a part thereof.

10 This invention relates to exterminators and the object of the invention is to improve the construction of exterminators of the type for which Letters Patent No. 1,239,799 were granted to me September 11, 1917.

15 Referring to the drawings which accompany this specification and form a part hereof, which drawings illustrate an embodiment of this invention and on which drawings the same reference characters are used to designate the same parts wherever they may appear in each of the several views, Figure 1 is a plan view of the exterminator, parts being omitted and parts being broken away; Fig. 2 is a vertical, transverse section taken 20 on the line 2—2 on Fig. 1, looking in the direction indicated by the arrows; Fig. 3 is a vertical, longitudinal section taken on the line 3—3 on Fig. 2, looking in the direction indicated by the arrows; Fig. 4 is an elevation of details, parts being shown in section; and Fig. 5 is a view similar to Fig. 4 but showing parts in different positions.

25 Referring to the drawings, the reference numeral 1 designates a main frame which may be of any suitable construction and which is illustrated by the drawings as composed of longitudinally, transversely and vertically disposed members which are suitably connected together and braced to form 30 a frame which is adapted to straddle a row of vegetation such as potato vines in hills, for example. The machine is provided with a pole 2 for draft animals and a seat 3 for the driver.

40 As the mechanism on one side of the exterminator is duplicated on the other side, except in a minor particular to be herein-after pointed out, the same reference characters will be applied to corresponding parts 45 on each side of the machine and a description of one side of the machine will describe both sides.

The reference numeral 4 designates a supporting and driving wheel which is fast to 50 the shaft 5. A supplemental frame 6 and a bearing 7 are supported by the shaft 5 and

the main frame 1 is supported upon the bearing 7 by the screwthreaded rod 8 and the nut 9. The screwthreaded rod 8 passes through holes in members of the main frame 60 and the nut 9 is provided with a collar 10 and a crank-handle 11. A strap 12 rests upon the collar 10 of the nut 9 and turning the crank-handle 11 lowers or raises the main frame 1 with respect to the wheel 4, 65 shaft 5 and supplemental frame 6 in a manner which will be readily understood from an inspection of the drawings. The main frame 1 is provided with guides 13 and 14 for the supplemental frame 6 and is also 70 provided with a vertically slotted guide 15 for the shaft 5 to relieve the rod 8 from bending strains. The shaft 5 has a gear 16 secured thereto and the supplemental frame 6 carries a shaft 17 to which are secured gear 18, pinion 19 and collars 20 and 21. Pinion 19 meshes with a gear 22, which is also carried by the supplemental frame 6, and a clutch-rod 23, which is provided with a yoke 24 engaging between the collars 20 75 and 21, can be pulled up and turned so that a finger 25 will rest upon an elevated part of the stop 26 and hold the gear 18 out of mesh with the driving gear 16. The gear 22 is provided with a crank-pin 27 which can 80 oscillate a lever 28 by means of the connecting-rod 29 and the bail 30. The supplemental frame 6 is provided with a slotted guide 31 for a pin 32 connected with the bail 30 and is provided with supports 33 and 34 for the fulcrum-pin 35 for the lever 28.

85 Bed plates 36 and collecting plates 37 are supported from the main frame 1 and slides 38 and 39 project outwardly from the bed plates. Crusher plates 40 are connected with the levers 28 by eye-bolts 41 and 42 which extend through alined holes in the levers 28 so that the crusher plates will be moved back and forth by said levers while permitting the eye-bolts to slide lengthwise through 90 said holes. Cam-plates 43 and 44 are pivoted to parts of the main frame 1 and have cam members 45 and 46 rigidly fastened thereto. Fingers 47 and 48 secured to the crusher plates 40 can slide under the cam 95 members 45 and 46, and elevate the cam members and cam plates, as clearly shown by Fig. 4 of the drawings, when the crusher plates are moved outwardly, but will ride up over the cam members 45 and 46 and lift 100 the crusher plates 40 above the bed plates 36 until the fingers clear the inner ends of 105

the cam members, as clearly shown by Fig. 5 of the drawings. Guards 49 may be secured to the slides 38 and 39 to prevent displacement of the cam plates. The collecting plates 37 are made of comparatively thin material and tappers 50 are provided for vibrating the collector plates to cause insects thereon to be moved down onto the bed plates. The tappers 50 are levers pivoted to 10 brackets 51 secured to members of the main frame 1. One end of a tapper is bent down through a hole in a collecting plate and has a head or nut on its end below the collecting plate. The other end of a tapper is provided 15 with a stop 52 adapted to engage under a bracket 51 and a clip 53 on a crusher plate is adapted to contact with a tapper, as the crushed plate falls toward the bed plate, and lift the head or nut to tap the collector 20 plate from below and vibrate the same.

Beaters 54, 55, 56, 57, 58 and 59 are adjustably secured to arms 60, 61, 62, 63, 64 and 65 which are fastened to shafts 66, 67 and 68. The shafts 66 and 68 are connected 25 with the shaft 67 by reverse motion connections 69 and 70 so that the beaters 56 and 57 will swing to one side and the other beaters will, at the same time, swing to the other side, so that a potato vine, for example, will 30 be brushed in one direction, then in the opposite direction and lastly in the first direction as the machine passes over it. The shaft 67 is rocked back and forth by a crank pin 71, on a pinion 19, which projects through a 35 hole in connecting-rod 72 and which reciprocates a slide 73 with which a crank 74, on shaft 67, engages.

The collecting plates 37 may extend in front of the main frame 1 and have their 40 ends turned up so that these plates will tend to slide over the ground and not dig in, if they contact with the ground. The projecting ends of these plates may be braced or stiffened in any suitable manner.

45 Aprons 75 are placed at each side of the machine to cause bugs or insects knocked off from the vines by the beaters to fall upon the collecting plates.

The operation of the exterminator will be 50 readily understood. As the machine is drawn along the beaters will be swung back and forth brushing the bugs or insects from the vines onto the collecting plates 37, the levers 28 will be rocked back and forth moving the crusher plates 40 out and in. As the 55 crusher plates are moved out the fingers 47 and 48 will slide under the cam-members 45 and 46, lifting the cam-members and the cam plates 43 and 44, and crush the bugs 60 on the bed plates and sweep them from the bed plates. As the crusher plates are moved in, the fingers 47 and 48 will ride up over the cam-members 45 and 46, thereby elevating the crusher plates, and, when the fingers 65 pass beyond the cam-members, the crusher

plates will fall upon the bed plates and crush the bugs thereon. When the crusher plates fall, the clips 53 will strike the tappers 50 and bring their heads up against the bottoms of the collecting plates and vibrate the same 70 and, as the collecting plates are inclined toward the bed plates, such vibrations will cause the bugs on the collecting plates to be moved down onto the bed plates. The beaters can be adjusted to suit the height of the 75 vines and by means of the crank-handles 11 the machine can be kept in an upright position when the wheels 4 are on different heights of ground. The clutch-rods 23 provide for throwing the gears 18 out of mesh 80 when the machine is being transported from one place to another.

What is claimed is:

1. The combination in an exterminator of a main frame, a bed plate, a crusher plate, 85 a shaft, a supporting and driving wheel thereon, a supplemental frame supported by said shaft and provided with mechanism to actuate said crusher plate, and means for adjusting said main frame with respect 90 to said shaft.

2. The combination in an exterminator of a main frame, a bed plate, a collecting plate, beaters, a crusher plate, a shaft, a supporting and driving wheel thereon, means to 95 actuate said beaters and said crusher plate, and means for adjusting said main frame with respect to said shaft.

3. The combination in an exterminator of a bed plate, a collecting plate, a crusher 100 plate, means to actuate said crusher plate and means to vibrate said collecting plate.

4. The combination in an exterminator of a bed plate, a crusher plate, gear mechanism for actuating said crusher plate, and a 105 clutch-rod for throwing gears out of mesh.

5. The combination in an exterminator of a collecting plate, a crusher plate, adjustable beaters, and means for actuating said beaters and crusher plate. 110

6. The combination in an exterminator of a main frame, bed plates, crusher plates, shafts, supporting and driving wheels on said shafts, supplemental frames supported on said shafts, gears secured to said shafts, 115 levers and gear mechanism carried by said supplemental frames for actuating said crusher plates, means for elevating said crusher plates as they are moved inwardly, and means for throwing the gear mechanism 120 out of mesh.

7. The combination in an exterminator of a plurality of shafts with beaters secured thereto, reverse motion connections between said shafts, and means for rocking one of 125 said shafts.

8. The combination in an exterminator of a main frame, a plurality of shafts with supporting and driving wheels and gear wheels thereon, a supplemental frame sup- 130

ported by each of said shafts, means for adjusting each of said shafts with respect to the main frame, bed plates and collector plates supported by the main frame, upright shafts carried by said supplemental frames and provided with gear wheels and pinions, means for moving said last mentioned shafts longitudinally, gear wheels meshing with said pinions, crusher plates, means for actu-

ating said crusher plates by said last mentioned gear wheels, beaters adjustable toward or away from the ground, and means to move some of the said beaters in one direction simultaneously with movement of other beaters in the opposite direction. 10 15

In witness whereof I hereto affix my signature.

HUBERT LONGAUER.
